PUMPING OR CIRCULATING SYSTEM.

Application filed February 27, 1928. Serial No. 257,373.

The present invention relates to pumping or circulating systems and while particularly well adapted for use in pumping or circulating lubricating mediums of internal combustion engines, in certain features is advantageous even where gas or air is to be pumped or compressed.

The principal objects of the invention are, to provide pumping or circulating systems which are positive in the feed or circulation of the lubricant or material, depending in no way upon non-positive or force-closed mechanisms, such as springs, check valves, etc., in the normal operation of the pumps or systems; to provide pumping or circulating systems which will remain operative and efficient for a great length of time, without attention, and hence particularly well adapted to installation in places not readily accessible, as within the housings or crank cases of internal combustion engines; and, to provide pumps or circulating systems requiring sumps of no great capacity, thus enabling the equipment to be used where the supply of material pumped or circulated is no greater than that usually supplied, from time to time, as to the crank cases or oil sumps of internal combustion engines.

Experience has shown that much damage to machines results from failure of the lubricating systems, either as the result of broken pipes or connections; failure of units, such as check valves to properly function; freezing or viscosity of the lubricant or contaminator, such as water when cold; or worn parts of the pumps which permit escape of the lubricant or fail to charge the pumps. It is another object of the invention to provide lubricating systems in which the lubricants are conducted thru elements of the pumps, avoiding the use of pipes, tubes, etc. As an example, individual elements of the pumps may function for a number of purposes, such as an eccentric operated piston rod functioning to reciprocate the piston, acts as a positive valve therewith, and conducts the lubricant from the cylinder to another element, to insure firm seating of the valve acting portion of the piston rod and the eccentric strap on its eccentric, even tho the parts may wear in time to some extent, and thus avoid loss of lubricant at relatively movable parts.

Other objects and advantages of the invention will appear in the following detailed de-

scription, taken in connection with the accompanying drawings, forming a part of this specification, and in which drawings:

Figure 1 is a view partly in elevation and partly in central vertical section thru an internal combustion engine equipped with a lubricating system according to the present invention.

Figure 2 is an enlarged view partly in end elevation and partly in vertical section thru the crank shaft and case, showing the major portion of the lubricating system.

Figure 3 is an enlarged detail view in central vertical section thru one of the units of the lubricating system, and showing the piston in a position during intake stroke.

Figure 4 is a similar view showing the piston and cooperating parts in a position for start of the exhaust stroke.

Figure 5 is a similar view, showing the piston and cooperating parts in a position during substantially one-half of such exhaust stroke.

Figure 6 is a similar view showing the piston as having completed the exhaust stroke and in a position to move for intake.

Figure 7 is a view on substantially the line 7—7 of Figure 3, but showing two of the units of the pump.

Figure 8 is a similar view but showing the piston rods removed to more clearly illustrate the piston heads.

In the drawings, A designates an internal combustion engine, including a main body portion B providing cylinders C, in which reciprocate pistons D having rods E connected to a crank shaft F, the latter revoluble in bearing G carried by bearing support H, all of which is similar to any of many makes and models of engines. In the example there is shown timing gears J and K, the former on shaft F, and the shaft F as well as the connecting rod E provided with ports L and M, respectively, which communicate for the purpose of lubricating various bearings of moving parts of the engine, as in a full force feed lubricating system. It is to be understood, however, that the foregoing is merely by way of example, since the present invention is applicable to engines of different types, such as aeroplane and marine engines, which differ in many instances from the type shown in the drawings, and in a broader sense, the present invention is applicable to pumping or circulating systems where the medium

pumped or circulated is not necessarily a lubricant.

In addition to the shaft F, and in the preferred form of the invention, the bearing support H, the system comprises eccentrics 10 and 11, cylinders 12 and 13, trunk pistons 14 and 15, and piston rods 16 and 17, including eccentric straps 18 and 19, respectively, there being also relief valves 20 associated with the cylinders 12 and 13 and a yoke 22, in the example shown rigidly connecting or supporting the cylinders 12 and 13 from the bearing support H. The system in the example shown also comprises an oil sump 23 preferably having a removable bottom plate 24, and an inclined runway 25 leading to sump 23.

The eccentrics 10 and 11 may be formed integral with shaft F, or may be rigidly secured therewith, in any suitable manner. Each eccentric is provided with an arcuate peripheral port 26 extending throughout an arc of substantially 180°, and communicating with a radial port 27 in shaft F, which radial port communicates with port L as shown in Figures 3-6. For compactness, symmetry, and balance, the eccentrics 10 and 11 are preferably disposed at opposite sides of bearing support H, as shown in Figure 1, which arrangement permits of ready removal of the timing gear J in the event that repair or replacement may be necessary. The eccentrics 10 and 11 are preferably arranged so that their throw sides are at opposite sides of the longitudinal axis of shaft F.

The cylinders 12 and 13 are preferably cast en bloc with a web of metal 29 between them, as shown in Figures 1, 7 and 8, the cylinders being spaced so as to dispose them with their longitudinal axes in the planes of the eccentrics 10 and 11. Yoke 22 has arms 30 integral with the web 29, and flanges 31 at the upper ends of arms 30, secured to bearing support H, as by machine screws 32, as shown in Figure 2. This arrangement provides a rigid support of the cylinders from the bearing support and yet permits ready access to the crank shaft bearing G.

Each cylinder is provided with one or more transverse ways 33 thru which liquid, such as the lubricant, may flow laterally into the cylinder, and not necessarily find its way thereto thru the open top 34 of the cylinder. The head 35 at the lower portion of the cylinder is provided with a removable plug 36 for the removal of foreign matter. Each cylinder has a longitudinally extending way 37 communicating with the bottom of the cylinder as at 38, and provided at its upper end with relief valve 20 for a purpose to be subsequently set forth.

It may be observed from Figures 1 and 2 that the cylinders 10 and 11 are disposed with their transverse ways 33, in the sump 23.

Referring now to the pistons 14 and 15, which are of the trunk type each is provided

with one or more transverse ways 39 in its skirt 40 these ways being relatively longer than the ways 33 in the cylinders, so as to communicate with the latter throughout the amplitude of movement of the pistons, and so that the skirts of the pistons will form no obstructions to passage of the liquid into the cylinders without passing over the upper portion of the latter. The heads 41 of the pistons 14 and 15 are provided with transverse thru ports 42 and 43 respectively, and the faces of the heads 41 enclosed by the skirts of the pistons are concaved as shown in Figures 3-6 along an arc struck from a center adjacent the upper margin of the piston, that is, the point 44 thru which the axis of oscillation of the respective connecting rod of the piston passes. If desired, the pistons and upper portions of the cylinders may be of the skeleton type for lightness, and inflow of the liquid to a point above the piston heads 41, without the necessity of the liquid reaching such point by passing over the upper ends of the cylinders.

As to the piston rods 16 and 17 they are each provided with a longitudinally extending port 50 open at ends 51 and 52 of the main body portion 53 of the rod, the end portion 52 acting as a valve for the port of its respective piston, and the end 51 of port 50 communicating at the proper time with the peripheral port 26 of its respective eccentric. The lower portion of port 50, or in other words, that portion adjacent the head of the piston is flared or enlarged so that full capacity of the piston head port may be utilized during the exhaust stroke of the piston. In the example shown, the eccentric straps 18 and 19 of the piston rods 16 and 17 are connected to yoke or strap portions 54 at the upper ends of the main body portions 53, as by bolts 55. The piston rods are pivotally connected to their respective pistons as by trunnions 56, the axes of which are in the line 44, from which the arc of the inner face of the piston head is struck, so that the valve acting lower portion of the piston rod, correspondingly shaped, will have good surface to surface contact with the piston head.

In practice, the ports 42 and 43 of the pistons 14 and 15 may be relatively long and narrow and still have considerable capacity for passage of the liquid from the cylinders. Such an arrangement also permits the valve acting piston rod to quickly open the ports for intake and exhaust of the liquid or gas, relative to the cylinder. Utilizing eccentrics for operating the piston rods results in rapid movement of the valve acting end of the respective connecting rod when the piston is just approaching the end of either stroke, and also enables the equipment to be applied to crank shafts without weakening same, and without the necessity of casting or otherwise providing cranks. An important feature of

the invention is that wear of parts results in those parts used for conducting the lubricant or liquid firmly seating. For instance, if the trunnions 56 of the piston rod should wear, 5 compression of the charge in the cylinder during the exhaust stroke has a tendency to more firmly seat the valve acting end of the piston rod on the inside surface of the piston head, as may be observed from Figure 5, where the 10 piston has descended substantially one-half the stroke for exhaust of the lubricant thru ports 42 and 50. At the same time, the yoke or strap 54 is pressed tightly against the lower surface of the eccentric 10, so as to prevent 15 escape of the lubricant laterally of the eccentric strap. During the intake stroke of the piston, as shown in Figure 3, and while the other piston is on its exhaust stroke, and hence forcing lubricant into the longitudinal 20 way L of the crank shaft F the throw side 28 of the eccentric 10 is ascending and therefore has a tendency to seal the space between the eccentric and the eccentric strap 18.

The ports 37 and 38, and the relief valve 20 25 is provided for the escape of some of the lubricant or liquid when cold and the viscosity is such as to retard its flow. The relief valve 20 functions like any relief valve, and may be of any suitable type.

30 While this invention provides for all requirements of the positive feed lubricating system for internal combustion engines, it is of course susceptible of application to other uses and realizing that the conditions con- 35 current with the adoption of the system will necessarily vary, it is desired to emphasize the fact that various minor changes in details of construction, proportion and arrangement of parts may be resorted to, when required, 40 without sacrificing any of the advantages of the invention, as defined in the appended claims.

We claim:

1. A pump comprising a shaft, a cylinder therebelow, provided with a head at its lower end and open at its upper end, a trunk piston in said cylinder provided with a thru port in its head, a piston rod operatively connected to said shaft and pivotally connected to said piston, to reciprocate the latter upon rotation of the former, the pivotal connection of the rod to the piston being intermediate the ends of the rod so that a portion of the rod extends to the inner face of the piston, said cylinder wall above the zone of reciprocation of the piston head, and the skirt of the piston, provided with transverse aligning openings thru which liquid may flow laterally into the cylinder and piston to the port of the latter, and the inner surface of the piston head concave and the lower end of the piston rod convex arcuately from the line of pivotal connection of the rod with the piston, whereby said rod acts as a valve for the port in the piston head.
2. A pump comprising, a shaft provided

with a longitudinal port, an eccentric on said shaft, provided with an arcuate peripheral port of substantially 180° communicating with the port of said shaft, a cylinder below said eccentric provided with a head at its lower end and open at its upper end, a trunk piston in said cylinder provided with a thru port in its head, a piston rod including an eccentric strap about said eccentric, said rod pivotally connected to said piston to reciprocate the latter upon rotation of the shaft, the pivotal connection of the rod to the piston being intermediate the ends of the rod so that a portion of the rod extends to the inner face of the piston, and the rod being hollow to provide a port from end to end, to communicate with the port of the eccentric during substantially one-half rotation of the latter, said cylinder wall above the zone of reciprocation of the piston head, and the skirt of the piston provided with transverse aligning openings thru which liquid may flow laterally into the cylinder and piston to the port in the latter, and the inner surface of the piston head concave and the lower end of the piston rod convex arcuately from the line of pivotal connection of the rod with the piston, whereby said rod acts as a valve for the port in the piston head and an outlet for liquid from the cylinder thru the piston head port to the port of said shaft.

3. A pump comprising, a shaft provided with a longitudinally extending port, an eccentric on said shaft provided with an arcuate peripheral port communicating with the port of said shaft, a cylinder below said eccentric provided with a head at its lower end and open at its upper end, a trunk piston in said cylinder provided with a thru port in its head, and a piston rod including an eccentric strap about said eccentric, said rod pivotally connected to said piston to reciprocate the latter upon rotation of the shaft, the pivotal connection of the rod to the piston being intermediate the ends of the rod, so that a portion of the rod extends to the inner face of the piston head, and the rod being hollow to provide a port from end to end, to communicate with the port of the eccentric, said cylinder wall above the zone of reciprocation of the piston head, and the skirt of the piston provided with transverse aligning openings thru which liquid may flow laterally into the cylinder and piston to the port of the latter, and the inner surface of the piston head concave and the lower end of the piston rod convex arcuately from the line of pivotal connection with the rod of the piston, whereby the said rod acts as a valve for the port in the piston head, and as an outlet for liquid from the cylinder thru the piston head port, to the port of said shaft.

4. A pump comprising, a shaft provided with a longitudinal port, an eccentric on said shaft, provided with an arcuate peripheral

port of substantially 180° communicating with the port of said shaft, a cylinder provided with a head at one end, and open at its end toward said shaft, a trunk piston in said cylinder provided with a thru port in its head, and a piston rod including an eccentric strap about said eccentric, said rod pivotally connected to said piston to reciprocate the latter upon rotation of the shaft, the pivotal connection of the rod to the piston being intermediate the ends of the rod so that a portion of the rod extends to the inner face of the piston head, and the rod being hollow to provide a port from end to end, to communicate with the port of the eccentric during substantially one-half rotation of the latter, and the inner surface of the piston head concave, and the lower end of the piston rod convex arcuately from the line of pivotal connection of the rod with the piston, whereby the said rod acts as a valve for the port in the piston head, and affords an outlet from the cylinder thru the port of said piston head, to the port of said shaft.

25. 5. In a lubricating system, a shaft provided with a longitudinal port, a bearing and bearing support for said shaft, two eccentrics on said shaft, said eccentrics at opposite sides of said bearing support and having throw sides at opposite sides of the axis of the shaft and provided with arcuate peripheral ports communicating with the port of said shaft, a pair of cylinders, one for each eccentric, means for rigidly supporting the cylinders from said bearing support with the longitudinal axes of the cylinders in the planes of their respective eccentrics, a trunk piston in each cylinder, each piston provided with a transverse thru port in its head, and a piston rod for each piston, each rod having its intermediate portion pivoted to its respective piston, and including an eccentric strap for its respective eccentric, each rod also provided with a longitudinal port open at the ends of the rod to communicate with the port in the eccentric during substantially a half turn thereof and having its lower end acting as a valve for the port of its respective piston.

6. In a lubricating system, a shaft provided with a longitudinal port, a bearing and bearing support for said shaft, an eccentric on said shaft provided with an arcuate peripheral port communicating with the port of said shaft, a cylinder, means for rigidly supporting the cylinder from said bearing support with the longitudinal axis of the cylinder in the plane of said eccentric, a trunk piston in said cylinder, said piston provided with a transverse thru port in its head, and a piston rod having its intermediate portion pivoted to said piston and including an eccentric strap about said eccentric, the rod also provided with a longitudinal port open at its ends to communicate with the port in the eccentric during substantially a half turn

thereof and having its lower end acting as a valve for the port in said piston.

7. In a lubricating system, a shaft provided with a longitudinal port, a bearing and bearing support for said shaft, two eccentrics on said shaft, said eccentrics at opposite sides of said bearing support and provided with arcuate peripheral ports communicating with the port of said shaft, a pair of cylinders, one for each eccentric, means for rigidly supporting the cylinders from said bearing support with the longitudinal axes of the cylinders in the planes of their respective eccentrics, a trunk piston in each cylinder, each piston provided with a transverse thru port in its head, and a piston rod for each piston, each rod having its intermediate portion pivoted to its respective piston, and including an eccentric strap for its respective eccentric, each rod also provided with a longitudinal port open at the ends of the rod to communicate with the port in the eccentric during substantially a half turn thereof and having its lower end acting as a valve for the port of its respective piston.

8. In a lubricating system, a shaft provided with a longitudinal port, a bearing and bearing support for said shaft, two eccentrics on said shaft having their throw sides off-set with respect to each other, and provided with arcuate peripheral ports communicating with the port of said shaft, a pair of cylinders, one for each eccentric, means for rigidly supporting the cylinders from said bearing support with the longitudinal axes of the cylinders in the planes of their respective eccentrics, a trunk piston in each cylinder, each piston provided with a transverse thru port in its head, and a piston rod for each piston, each rod having its intermediate portion pivoted to its respective piston, and including an eccentric strap for its respective eccentric, each rod also provided with a longitudinal port open at the ends of the rod to communicate with the port in the eccentric during substantially a half turn thereof and having its lower end acting as a valve for the port of its respective piston.

9. In a lubricating system, a shaft provided with a longitudinal port, two eccentrics on said shaft having throw sides at opposite sides of the axis of the shaft and provided with arcuate peripheral ports communicating with the port of said shaft, a pair of rigidly mounted cylinders, one for each eccentric, with the longitudinal axes of the cylinders in the planes of their respective eccentrics, a trunk piston in each cylinder, each piston provided with a transverse thru port in its head, and a piston rod for each piston, each rod having its intermediate portion pivoted to its respective piston, and including an eccentric strap for its respective eccentric, each rod also provided with a longitudinal port open at the ends of the rod to communicate with the port in the eccentric during substantially a half turn thereof and having its lower end acting as a valve for the port of its respective piston.

- cate with the port in the eccentric during substantially a half turn thereof and having its lower end acting as a valve for the port of its respective piston.
5. 10. In a lubricating system, a shaft provided with a longitudinal port, two eccentrics on said shaft and having throw sides at opposite sides of the axis of said shaft and provided with arcuate peripheral ports communicating with the port of said shaft, a sump for lubricant beneath said shaft, a pair of cylinders, one for each eccentric, rigidly mounted below said shaft and extending into said sump, a trunk piston in each cylinder 10 provided with a thru port in its head, and a piston rod for each piston, each rod having an intermediate portion pivoted to its re-

spective piston and including an eccentric strap for its respective eccentric, each rod also provided with a longitudinal port open 20 at the ends of the rod to communicate with the port in the eccentric during substantially a half turn thereof and having its lower end acting as a valve for the port of its respective piston, said cylinder walls above the zones of reciprocation of the piston heads therein, and the skirts of the pistons provided with transverse aligning openings thru which the lubricant may flow laterally from the sump into the cylinders and pistons to the 25 ports in the latter.
